SEWING MACHINE

Paul P. Kessler, Chicago, Ill.

Original application February 10, 1936, Serial No.
63,048. Divided and this application May 5,
1936, Serial No. 78,051

4 Claims. (Cl. 112—214)

This is a divisional application from the original filed on February 10, 1936, Serial Number 63,048 for Sewing machine.

My invention relates to a feeding mechanism for a sewing machine. Among the objects of my invention are the following: To create a sewing machine having dual feed rollers in which each of said feed rollers is independently and automatically adjustable regardless of the material of different thicknesses fed simultaneously to each of said feed rollers, so that said different thicknesses of material may be sewn simultaneously together edge to edge. To supply a sewing machine so constructed that it can be shifted from a ratchet regulation to a clutch regulation and vice versa, thereby providing a machine adapted to create various sizes of stitches, and such other objects, advantages and capabilities as will later more fully appear and which are inherently possessed by my invention.

While I have shown in the accompanying drawings a preferred embodiment of my invention, yet I wish it understood that the same is susceptible of modification and change without departing from the spirit of my invention.

Referring to the drawings, Fig. 1 is a front elevation of the sewing machine embodying the features of my invention. Fig. 2 is a vertical section of my feeding mechanism. Fig. 3 is a fragmentary side elevation showing my roller clutch mechanism. Fig. 4 is a front view showing the feeding plate in position for edge to edge sewing. Fig. 5 is a side elevation of my sewing machine embodying the features of my invention. Fig. 6 is a detailed view of my feeding mechanism.

In the embodiment selected to illustrate my invention the lower portion 11 of the frame 10 of a sewing machine houses the feeding mechanism 37 which comprises the combination of a roller structure 21, a ratchet 35 and a roller clutch mechanism 23. My roller structure 21 includes a pair of rollers 24 and 25. An adjustable center guide 26 is placed between the rollers 24 and 25. My rollers 24 and 25 are, of course, driven as one unit but they are separately and automatically adjustable to accommodate different thicknesses of cloth to be fed by the rollers for the sewing operation. Each of my rollers 24 and 25 has a hollow portion 27 adapted to receive a ball shaped bearing 28. Each of said rollers has its hollowed out portion 27 extended to form a pair of oppositely disposed grooves 29 to receive a pair of oppositely disposed driving pins 30 of the ball shaped bearing 28. It will be noted that in operation when a piece of goods having a certain

thickness is to be sewed to another piece of a different thickness and said pieces are placed edge to edge on my feeding mechanism each of my two feed rollers will automatically and separately yield on their respective ball shaped bearings to compensate for the different thicknesses of the material. For example, when a thick piece of goods is to be sewed to a thin piece of goods so that the thin piece of goods is fed by one roller and the thick piece of goods is fed by the other roller, one roller will apply pressure to the thin piece of goods separately from the other roller which will move on its bearing to accommodate the thick piece of goods so that both pieces are accommodated and receive substantially the same feed pressure during the sewing operation. With my device there is even feeding regardless of different thicknesses of goods fed to either of the two rollers. My rollers 24 and 25 furthermore are movable together against the action of springs 82, so as to accommodate different thicknesses of material to be sewed.

My invention also comprises two distinct stitch controls, one is a stitching regulator by ratchet movement and the other is a stitch regulator by clutch control. My machine is so constructed that I can shift from the ratchet regulator to the clutch regulator and vice versa, thereby providing a machine adapted to create various sizes of stitches.

An eccentric 32 is mounted on the upper portion 12 of the frame 10 and has an arm 67 extending downwardly which is pivoted to a ratchet connection 33 which passes through the lower bed 11 and in turn is pivoted to a ratchet member 34 for operative engagement with a ratchet wheel 35 of the feeding mechanism 37. The arm 67 at its lower end is provided with a screw 39 which is adjustably secured within a slot 38 in the ratchet connection 33. Said member 39 may be set within slot 38 at certain desired positions for shortening and lengthening the stitch. Actuated by an eccentric on the drive shaft supported on the upper portion 12 is a member 40 which is connected to a different adjustable connection 41 which contacts and actuates a clutch roller 23 attached to the roller mechanism 21. With my roller clutch 23 the operator may obtain any desired length of stitch at his discretion, within the limits of adjustment of set screw 86 within slot 87.

When the ratchet mechanism is used there are three separate and distinct sizes of stitches, each one of which may be chosen by the operator. When the screw 39 is in the outermost position in

slot 38, the ratchet carrier feeds to the extent of one notch of the ratchet; when the screw 39 is in an intermediate position in slot 38 the ratchet carrier feeds to the extent of two notches of the ratchet; and when the screw 39 is in the innermost position in slot 38 the ratchet carrier feeds to the extent of three notches of the ratchet. When the roller clutch mechanism is employed the stitch is not set or definite but may be regulated by the discretion of the operator from the smallest up to a maximum point depending upon the adjustment of the adjustable connection 41. The reverse operation is obvious.

The ratchet mechanism is disconnected by manually turning a lever 90 attached to the lower bed 11 adjacent ratchet arm 34 so that lever 90 moves said ratchet arm 34 to a position out of engagement with ratchet wheel 35. When lever 90 is moved back spring 91 pulls ratchet arm 34 back to normal position so that it engages ratchet wheel 35 for operation.

The roller clutch mechanism may be made inoperative by the user by positioning the set screw 86 in the lowermost part of slot 87, which places it in dead center so that the driving mechanism 88 does not operate.

Having thus described my invention, I claim:

1. In a sewing machine a pair of feed rollers, each of said feed rollers having a hollow portion, and a pair of oppositely disposed grooves, a ball shaped bearing, having a pair of oppositely disposed driving pins, said bearing and said pins adapted to fit into the hollow portion and grooves of said rollers, said rollers being driven as a unit and each of said rollers adapted to yield

on its bearing automatically and independently from the other roller to accommodate material of a different thickness than that fed simultaneously to the other roller.

2. A feeding mechanism for sewing machines comprising a pair of flexibly connected and independently yieldable feed rollers rotatably journaled in vertically movable supports, and yieldable means operatively engaged with said supports. 10

3. A feeding mechanism for a sewing machine comprising rotary drive means, a feed roller driven by and having a universal connection with said drive means, and a second feed roller driven by said first roller and having a universal connection therewith. 15

4. In a sewing machine, a roller feed member, a ratchet wheel and roller clutch operatively connected with the roller feed member, a drive shaft, a pawl for actuating said ratchet wheel, 20 adjustable means driven by said drive shaft and operatively connected with said pawl, drive connections between said drive shaft and said roller clutch, means for throwing said pawl into and out of driving engagement with said ratchet wheel and means for throwing said drive connections into and out of driving connections with said roller clutch, said roller feed member advancing the fabric for predetermined length of 25 stitches when operated by said ratchet wheel and pawl mechanism and advancing the fabric for lengths of stitches intermediate said predetermined lengths when operated by said roller clutch. 30
